UNITED STATES PATENT OFFICE.

JOSEPH S. JONES AND SAMUEL N. MEAD, JR., OF BROOKLYN, NEW YORK, ASSIGNEES
TO CHAS. CORY & SON, INCORPORATED, OF NEW YORK, N. Y., A CORPORATION OF
NEW YORK.

ELECTRICAL FITTING.

Application filed June 11, 1923. Serial No. 644,627.

Our invention relates to improvements in electrical fittings or fixtures.

A principal object of the invention is to provide a new and improved combined lamp 5 or plug socket and switch.

Another important object is to provide a lamp socket or analogous electrical connection or fitting, in combination with an oil- and gas-tight "box" or enclosure for circuit 10 connections or a switch.

Another object is to provide modifications and improvements in double pole switches of the type disclosed in the patent to Frank W. Wood, No. 1,094,690, April 28, 1914, and 15 particularly to adapt a switch of that type to a lamp socket or similar electrical fitting.

To accomplish these and other objects, the invention in one representative embodiment, as briefly described, comprises a combined 20 lamp socket and switch base with suitable switch mechanism mounted on the base, a switch box in which the switch with suitable circuit terminals is located, a switch handle accessible at the outside of the box, 25 and suitable operating connections, and provisions for making the box substantially or completely oil- and gas-tight, for the purpose of eliminating fire and explosion risks.

The characteristics and advantages of the 30 invention are further sufficiently explained in connection with the following detail description of the accompanying drawings, which show one exemplifying embodiment of the invention. After considering this embodiment, it will be evident to persons skilled in the art that many variations 35 may be made within the principles of the invention, and we contemplate the employment of any structures that are properly 40 within the scope of the appended claims.

Figure 1 is a vertical section of an electrical fixture embodying the invention in one form.

Figure 2 is a horizontal section through 45 the switch-box.

Figure 3 is a vertical section of the socket, switch and operating mechanism in the plane of the switch rotor axis.

Figure 4 is a section of the socket and 50 switch in a plane at a right angle to that of Figure 3.

Figure 5 is a detail section of the switch 55 rotor in operative relation to one of the movable contacts.

A socket body 1 of suitable insulating ma-

terial, such as porcelain or other molded composition, is provided with a socket sleeve or housing 2 and a flanged base 3. A contact base 4, which in the present embodiment of the invention is a switch base, of 60 any suitable insulating material, is associated with the socket body and secured thereto by rivets or screws 5, the heads of which are located in sockets 6 in the switch base and the threaded portions of which 65 preferably engage in metallic members 7, located in suitable sockets in the base of the socket body.

The contact members in the socket body may vary in accordance with the purpose 70 for which the fixture is designed. In a preferred embodiment of the invention the socket portion of the fixture is designed to receive an electric bulb or a screw plug attached to an electric "cord." For this purpose a metallic shell 8, screw threaded or pressed to a thread-like formation, is located within the socket housing 2 and preferably this contact shell is entirely free from the socket body and is mounted on the 75 switch base 4. This mounting or attachment of the threaded shell consists, in the present example, of screws 9 and 10 and nuts 11, the screws passing through the switch base and through inturned flanges of 80 the contact shell 8 and the nuts engaging below the flanges. A circuit connection to the upper side of the switch base is provided by one of the fastening screws such as 10, which passes through an offset portion 90 12 of a flat metal contact or conductor 13 located on top of the switch base. A central socket contact member or button 14, formed as a part of a substantially U- 95 shaped metallic conductor 15 is secured by 95 a screw 16 to the switch base, and this screw, to provide a circuit connection, also passes through an offset portion 17 of a flat metal contact member or conductor 18 located on top of the switch base. Desirably the bottom face of the switch base is provided with a substantially U-shaped or semi-circular flange 19 to enclose an inner part 15 of the central socket contact.

The various contacts or metallic conductors so far described, are merely representative of suitable contacts or connections which may be provided in various forms for different adaptations of the combined socket and contact or circuit connection devices. In a 110

preferred embodiment of the invention, however, and especially when it is adapted for a lamp fixture as in the present specific example, the insulating body 4 is not merely a contact or conductor base, but a switch base, and the conductors 13 and 18 are associated with the movable switch members 20, two of these being provided, since a double-pole switch is desirable and preferred for many reasons. Each switch member 20 is bent into substantially U-form at 21 to provide a base portion 22 secured to one of the conductors, either 13 or 18, by screws or rivets 23. At the other end each switch member is bent into U-form at 24 to provide a contact member 25 adapted to yieldingly and closely engage a fixed contact or terminal 26, one of these being provided for each switch member. The terminals or fixed contacts 26 are secured to the upper or outer end of the switch base by screws 27, which may serve at the same time as binding screws to secure the ends of conductor wires to the fixed contacts. Desirably the outward ends of the contacts are turned up as at 28 to facilitate the proper electrical connection between the contact members and the conductors when the latter are clamped down by the screws.

30 The movable switch members are operated by a rotor 30 of suitable insulating material, which is rotatably mounted on a shaft 31, and the shaft is rotatably supported in brackets 32 having angular bases 33 secured to the switch base by screws or rivets 34. The rotor is connected to turn with shaft 31 with a suitable amount of lost motion, by a screw-pin 35 inserted in a threaded hole in the shaft, and located in a slot 36 of the rotor. The central portion 37 of the rotor in which slot 36 is located may be substantially circular in cross section. At each side of it is a substantially oval or cam portion 38, the smaller diametral width of which is such that when the rotor is in the position shown in Figure 5, the switch members 20 spring upward and break contact between their ends 25 and the fixed contacts 26, to break the circuit. Cam portions 38 of the rotor have, in line with their longer axis, small flat portions or lands 39, so that when the rotor is turned to a position at a right angle to that shown in Figure 5, one of the lands or flat portions 39 engages the corresponding switch member and holds the movable contact portions 25 yieldingly and firmly in engagement with the fixed contacts 36, to close the circuit. The lost-motion device provides in a simple way an effective snap action to insure quick separation of the contacts when the switch is opened. A suitable handle and operating connection are provided as hereinafter described.

When an electrical fitting or fixture of the present type is used in a great many loca-

tions, for instance locations where oil or gas is present and might cause fire or explosion by access to loose circuit connections, it is desirable to provide a housing which will substantially or entirely prevent access of oil or gas to such connections, and this is particularly desirable when the circuit connections are, as in the present preferred embodiment of our invention, in the form of a switch, and sparks are usually drawn at the switch contacts when the circuit is broken. For this purpose and also to provide a secure and tight enclosure for the switch mechanism to prevent it from mechanical injury and access of water or moisture, as well as gas and oil, and also to provide a suitable base or mounting for the combined socket and switch or circuit base 4, the combined socket and switch base is mounted on a switch box 40, which is usually of metal of substantial thickness. This box has an upper or outer end wall 41 which is desirably solid or entirely free from apertures, and a side wall or walls 42. This side wall may be contoured to provide a box of any suitable shape such as square, polygonal or round, a round box being selected for illustration, and in that case the side wall 42 is of circular cross section and is usually made of very substantial thickness. Opposite to end wall 41, the box has an inwardly projecting flange 43 surrounding an aperture 44 properly shaped to accommodate the switch base 4, which is inserted in the aperture and the switch mechanism with its contacts and circuit connections is then located entirely within the box. Flange 3 of the socket body lies below or outside flange 43 and desirably a washer or gasket 45 of any suitable material, such as rubber or rubber composition, or of other suitable compressible material which is impervious to oil if the fixture is exposed to oil, is placed between flange 43 and the socket flange and the socket flange is secured to the box by screws 46 passing through suitable holes 47 in the socket flange and engaging in the box flange 43. By setting these screws up tight an oil- and gas-tight joint is provided which effectively prevents access to the interior of the box of oil, gas, or moisture.

Desirably the box has a cylindrical extension 50 suitably threaded to receive a glass globe 51 when it is desired to use such a globe to enclose and protect the lamp bulb 52, and the gasket or washer 45 is preferably of a sufficient diameter so that the inner end of the globe will bear against it and exclude oil or moisture from the interior of the globe. Desirably also the outward end of extension 50 is recessed to receive the collar 51 of any ordinary or suitable globe protector 52. A set screw 53 is also usually provided to secure the globe protector in position.

The side wall 42 of the box is provided with one or any suitable number of openings 60 to admit conductors and usually these openings are screw threaded to receive the threaded ends of metallic conduits 61, Figure 2, and any of the openings 60 which are not in use may be tightly closed, as by screw plugs 62. A conduit, such as 61, is usually inserted in a position which is convenient for bringing the enclosed conductor wires to the binding screws 27, as shown in Figure 2. It is usually convenient to provide four of the openings 60 spaced equally around the side wall of the box.

15 While any suitable operating device having an exterior handle may be provided to operate the switch, preferably improved operating mechanism is provided which allows for any slight disalignment between the switch shaft 31 and the operating mechanism; the operating mechanism is moreover designed so that it may be conveniently located in any one of the apertures 60 and also so that it may be tightly packed to prevent entrance of oil or gas. In the present embodiment of the invention, the operating device comprises a stem 70 passing through a stuffing box which comprises an outer member 71 screwed into one of the apertures 60 and an inner member 72 screwed into the outer member and arranged to properly compress any suitable packing 73 around the stem. On the inward end of stem 70 is formed or secured a jaw member 74, the jaws 75 of which are located with slight clearance against any two opposite faces of a square head 76 formed on one end of the switch shaft 31. A spring 77 located about an inner portion of stem 70 serves to take up unnecessary play and to hold the inward end of the stem against the outer end of shaft head 76. Any suitable handle or finger knob 78 is secured to the outer end of the stem, outside the switch box. The square head 76 and jaw member 74 provide in effect a universal connection between the stem and the switch shaft, and allow for moderate disalignment of these members.

40 The described operating device and connection provides in an obvious way for insert-

ing and connecting the operating device to the switch shaft when the socket and switch body are attached to the switch box in any of the possible positions.

55

The described construction and arrangement provides for a complete and secure oil- and gas-tight enclosure of the switch mechanism so that oil or gas cannot get inside the box, and sparks which occur when the switch circuit is broken cannot ignite gas or oil in the neighborhood of the box. The provision of a double-pole switch in the present simple and durable form also renders the exteriorly accessible contacts (socket contacts) completely dead when the switch is open.

60

65

We claim:

1. An electrical fitting including a tubular body and a contact base closing one end of the body, said base and body of insulating material, the base carrying an internally threaded socket extending into the body, fixed and movable contacts on the face of the base remote from the body, the movable contacts being normally spring urged to open position, and a rotor journaled on the base above the movable contacts and having cam portions to move the contacts to closed position.

70

2. An electrical fitting including a tubular body and a contact base closing one end of the body, said base and body of insulating material, the base carrying an internally threaded socket extending into the body, fixed and movable contacts on the face of the base remote from the body, the movable contacts being normally spring urged to open position, a rotor journaled on the base above the movable contacts and having cam portions to move the contacts into closed position, a closed casing having a fluid tight connection with the exterior of the body, and mechanism extending through a wall of the casing for operating the rotor, and having a fluid tight connection with said wall.
